UNITED STATES PATENT OFFICE.

NATHAN A. HEACOCK, OF SULLIVAN, ILLINOIS.

STOCK FEEDER.

Application filed April 12, 1920. Serial No. 373,218.

To all whom it may concern:

Be it known that I, NATHAN A. HEACOCK, a citizen of the United States, residing at Sullivan, in the county of Moultrie and State of Illinois, have invented certain new and useful Improvements in Stock Feeders, of which the following is a specification.

This invention relates to an improved stock feeder and has as its primary object 10 to provide a device of this character particularly adapted for feeding hogs or sheep.

The invention has as a further object to provide a stock feeder embodying a trough having a hopper swingingly mounted thereon and wherein guards will be provided to 15 extend between the hopper and trough for normally holding the hopper against swinging movement.

And the invention has as a still further 20 object to provide a feeder wherein the trough may be readily cleaned.

Other and incidental objects will appear as the description proceeds and in the drawings wherein I have illustrated the preferred embodiment of the invention and wherein similar reference characters designate corresponding parts throughout the several views:

Figure 1 is a perspective view of my improved feeder, and

Figure 2 is a transverse sectional view more particularly showing the mounting of the hopper.

In carrying out the invention, I employ a 35 trough 10 provided with sides 11 and the ends of which are extended upwardly to form standards 12. The trough may, of course, be constructed of any suitable material and varied in dimensions as desired.

40 In connection with the trough I provide a hopper 13 having downwardly converging side walls which merge into a spout 14 at the lower end of the hopper. At its upper end, the hopper is equipped with a top wall 45 15 and hingedly connected to this top wall is a lid 16 normally closing the hopper at its upper extremity. The hopper is of a length to be freely received between the standards 12 of the trough, as shown in Figure 1 and

50 detachably supporting the hopper upon the trough is a pivot rod or hanger 17. This rod is arranged to extend horizontally through the hopper adjacent its upper extremity and, at its ends, projects beyond the 55 end walls of the hopper to engage in suitable slots 18 formed in the upper edges of

the trough standards 12. Thus, it will be seen that the hopper may be removed from the trough by simply lifting the hopper upwardly therefrom. Normally holding the 60 hopper against displacement as well as locking the hopper against swinging movement upon the rod 17, are locking pins or keys 19. These pins are removably fitted through the standards 12 of the trough to engage, at 65 their inner extremities, in suitable openings in the end walls of the hopper. Consequently, the said pins will act to rigidly connect the hopper with the trough. Hinged to the side walls of the hopper adjacent the 70 lower extremities thereof, are guards 20 each of which preferably includes parallel side rails and a suitable number of spaced cross slats. The guards, when in normal position, are arranged to extend between the 75 lower extremity of the hopper and the sides 11 of the trough and, as particularly shown in Figure 2, the outer side rails of the said guards are arranged to snugly engage over the said side walls of the trough for preventing accidental upward displacement of the 80 said guards.

The trough and hopper, as thus described, are, when assembled, particularly designed to provide a feeder for hogs. By opening 85 the lid 16 of the hopper, feed may be introduced therein to be directed through the spout 14 into the trough and, of course, the guards 20 are designed to prevent the hogs from climbing into the trough. When it is 90 desired to clean the trough, the said guards may simply be swung upwardly and the pins 19 removed when the hopper may be swung upon the rod 17 in either one direction or the other to project laterally 95 from the trough and permit easy access thereto. Obviously, this provides a very advantageous arrangement and for supporting the hopper, when thus swung laterally, one of the pins 19 may, if desired, be connected with one of the end walls of the 100 hopper to engage an adjacent edge of one of the trough standards.

Having thus described the invention, what is claimed as new is:

1. A stock feeder including a trough having standards, a hopper pivotally supported by the standards therebetween, and a pin fitting through one of the standards to engage the hopper normally locking the hopper against pivotal movement, the hopper being adapted to be swung laterally with

respect to the trough and said pin being removable for engagement with the hopper to coact with an edge of one of the standards for sustaining the hopper when swung laterally.

2. In a stock feeder, the combination of a trough provided with standards, a hopper, a hanger coacting with said standards swingingly supporting the hopper between 10 the standards over the trough, and guards extending between the hopper and trough normally holding the hopper against swinging movement.

3. In a stock feeder, the combination with 15 a trough provided with standards having slots opening through the upper ends of the standards, a hopper, a hanger engaging in said slots swingingly supporting the hopper

between the standards over the trough, and means normally locking the hopper against 20 swinging movement as well as upward movement whereby to limit the hanger against displacement from said slots.

4. In a stock feeder, the combination of a trough having standards and provided with 25 sides, a hanger swingingly supporting the hopper upon the standards over the trough, and guards pivoted upon the hopper at opposite sides thereof and having rails normally engaging over the sides of the trough 30 coacting therewith for holding the guards against accidental upward displacement as well as holding the hopper against swinging movement.

In testimony whereof I affix my signature. 35
NATHAN A. HEACOCK.
